SLIP COVER FASTENER OR STABILIZER

Filed Aug. 17, 1945

Inventor,
J. W. Smith.

By Sterling P. Buck,
Attorney.

UNITED STATES PATENT OFFICE

2,537,100

SLIP-COVER FASTENER OR STABILIZER

James Walter Smith, Baltimore, Md.

Application August 17, 1945, Serial No. 611,015

4 Claims. (Cl. 155—182)

1

This invention relates to a slip-cover fastener or stabilizer, and especially to a normally concealed fastener which is easily adjustable to compensate for shrinkage or stretching of the material of which slip-covers are made.

Where slip-covers are used on chairs, sofas, etc., the ordinary use of such articles of furniture causes the front part of the canopy of the back-rest to gradually become wrinkled while the rear skirt of the canopy is raised and slides over the back-rest; such wrinkling is not only unsightly, but also causes the slip cover to wear and tear more quickly than if the wrinkles were prevented.

Therefore: The main object of this invention is to provide a simple and very effective means to stabilize the canopy so it cannot thus become wrinkled and prematurely worn or torn.

A further object is to provide a comparatively simple, inexpensive and conveniently applied and adjusted device that is normally out of sight, and which adds only a slight expense to the cost of each of such slip-covers.

Other objects and important features are pointed out or implied in the following details of description, in connection with the accompanying drawings in which,

Fig. 1 is a left-side elevation of an upholstered seat having a slip-cover thereon, the lower part of the latter and a portion of the seat being broken away and in cross-section; my fastener being shown partly in dotted lines and partly in full lines.

Fig. 2 is a view showing a fragment of the rear skirt as seen from its front or inner side, with the securing or stabilizing device hanging therefrom.

Fig. 3 is a greatly enlarged sectional view taken along the line 3—3 of Fig. 2.

Fig. 4 is a much enlarged left-side view of one form of anchoring unit, a part broken out, this being only slightly different from the form shown in Fig. 1.

Fig. 5 is a horizontal sectional view taken along the line 5—5 of Fig. 4.

Fig. 6 illustrates a modified form of anchoring unit engaged with a strip or tape of fabric secured in one of its various adjustments by a barb on the anchoring unit.

Fig. 7 is a sectional view taken thru the center of the anchoring device of Fig. 6.

Referring to these drawings in detail, in which similar reference numerals refer to similar parts in the several views, the invention is described in detail as follows:

The back-rest of the furniture-unit is indi-

cated at 10, the seat-frame at 11, and the upholstering at 12. The slip-cover 13 includes a canopy 14 having a rear skirt 15 secured by stitching 16 to the upper section 17, and to the flange of a bead or piping 18.

The slip-cover-fastener includes an angular piece or duplex unit of fabric 19 having its upper edge portion secured to the upper part of the skirt 15 and to the upper section 17; and, for sake of economy, its securing means may well constitute or include the same stitching 16 that secures the fabric-units or sections 15, 17 and 18 to one another. The lateral or upright edges of the unit 19 has its margins turned inward and stitched at 20, so they are reenforced against tearing or undue stretching; and they converge downwardly to a relatively short lower edge to which a fabric tape or strap 21 is secured by any appropriate means, for instance, seams of stitching as at 22.

A barbed anchoring unit 23 has a loop 24 at its upper end, and a barb 25 near its lower end and normally embodied in the under-side of the seat-frame while its loop 24 is engaged with a tied knot 21a of the tape 21. This anchoring unit is only slightly different from the one shown in Fig. 4 where the loop 24a is at right-angles to that of Fig. 1; so a broad description of Fig. 4 is also readable on the anchoring unit of Fig. 1, and is as follows: The anchoring device or unit is formed of a length of wire that has a loop (24a in Fig. 4) at the upper end and a loop or annulus 26 substantially at its lower end. The shank 27 is bent at right-angles at 28, and the horizontal part 29 of the shank is under and against the wire-end-portion 30 that terminates in the upwardly tapered sharp-pointed barb 25 which latter is substantially parallel with the main portion of the shank 27.

While this form of anchoring unit, above described, is very convenient and effective, because it can be applied without aid of any tool, by pressure of a thumb for causing the barb to enter the under side of the seat-frame; also because the loop 24 or 24a stands out from the seat-frame to permit the tape 21 to be readily adjusted and tied; the invention is not limited to this form; and as an example of another form that may be very effective and at less cost, reference is made to the barbed anchoring unit of Fig. 6 and 7, which latter unit is capable of being cast, molded or pressed into the shape shown, viz., comprising a relatively thin and wide element having a central portion 31 that includes a barb 32 rigidly united therewith and has large

openings 33 at opposite sides of said central portion, these openings extending approximately to the periphery of this unit.

With either form of anchoring unit, adjustments can be made either by properly tying the tape to the upper loop (Figs. 1, 2, 4) or to the peripheral segments of the unit of Figs. 6 and 7; or by causing the barb 25 or 32 to pierce the tape at different points for different adjustments.

Although these different forms of anchoring device have been specifically described, the invention is not limited thereto or thereby; for various changes may be made within the scope of the inventive ideas as implied and claimed.

I claim the following as my invention:

1. The combination, with a slip-cover canopy including an upper section, a rear skirt, and stitching connecting the upper edge of the skirt to the rear edge of the upper section, of a slip-cover stabilizer comprising a connector member joined at its upper end by said stitching to the rear edge of the upper section and extended downwardly inside the canopy, and means at the lower end of said member adapted for connection to a seat frame.

2. The combination, with a slip-cover canopy including an upper section, a rear skirt, and stitching connecting the upper edge of the skirt to the rear edge of the upper section, of a slip-cover stabilizer comprising an elongated flexible member joined at its upper end by said stitching to the rear edge of the upper section, and means at the lower end of said member adapted for connection to a seat frame.

3. The combination, with a slip-cover canopy including an upper section, a rear skirt, and stitching connecting the upper edge of the skirt to the rear edge of the upper section, of a slip-cover stabilizer comprising a fabric connector member including a wide piece of fabric joined at its upper end to the rear edge of the upper section; a tape connected at one end to the lower end of said wide piece, and means at the other end of said tape adapted for connection to a seat frame, all portions of said connector mem-

ber being disposed inside the canopy and proportioned to be concealed by the rear skirt of the canopy.

4. The combination, with a slip-cover canopy including an upper section, a rear skirt, and a line of stitching connecting the upper edge of the skirt to the rear edge of the upper section, of a slip cover stabilizer comprising a connector member that includes an approximately triangular piece of material joined along one end by said line of stitching to the rear edge of the upper section, an elongated tape joined at one end to the other end of said triangular piece, and means at the other end of the tape adapted for connection to a seat frame, all portions of said connector member being disposed inside the canopy and concealed by the rear skirt thereof.

JAMES WALTER SMITH.
